[57] CLAIM

The ornamental design for a stepped-recess food container, as shown and described.

DESCRIPTION

FIG. 1 is a perspective view of the bottom and sides of a stepped-recess food container showing my new design; FIG. 2 is a perspective view of the top and sides thereof; FIG. 3 is a side elevational view thereof, all four sides being identical;

FIG. 4 is a bottom plan view thereof;

FIG. 5 is a top plan view thereof; and,

FIG. 6 is a perspective view of the top and sides from a different angle than FIG. 2.
